CLAIM

The ornamental design for a connector spacer as shown and described.

DESCRIPTION

FIG. 1 is a perspective view of a connector spacer showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view thereof;

FIG. 9 is a perspective view of a connector spacer in a condition of use;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof;

FIG. 16 is a perspective view of a connector spacer in a condition of use; and,

FIG. 17 is a perspective view of a connector spacer in a condition of use.

(Continued)

The broken lines shown in the figures are for the purpose of illustrating portions of the connector spacer and form no part of the claimed design.
